CLAIM

The ornamental design for the lid for food storage container, as shown and described.

DESCRIPTION

FIG. 1 is a front perspective view of the lid for food storage container illustrating the lid when attached to the food storage container;

FIG. 2 is a front view thereof;

FIG. 3 is a rear view thereof;

FIG. 4 is left side view thereof;

FIG. 5 is a right side view thereof; and,

FIG. 6 is a top view thereof.

The broken lines depict portions of the lid for food storage container that form no part of the claimed design.
